HANGING CANDLE HOLDER

Albert J. Gaydick, 8748 Farralone Ave.,
Canoga Park, Calif. 91304

Filed June 21, 1973, Ser. No. 372,163

Term of patent 14 years

Int. Cl. D26—01

U.S. Cl. D48—2

Fig. 1.

Fig. 3.

Fig. 2.

Fig. 4.

FIG. 1 is a side elevational view of a hanging candle holder showing my new design, the candles being shown in broken lines for illustrative purposes only;

FIG. 2 is a top plan view thereof;

FIG. 3 is an elevational view of the side opposite that shown in FIG. 1;

FIG. 4 is a bottom plan view thereof;

FIG. 5 is a cross-sectional view taken on line 5—5 of FIG. 3;

FIG. 6 is a side elevational view of a second embodiment of my design; and

FIG. 7 is a top plan view thereof.

I claim:

The ornamental design for a hanging candle holder, substantially as shown and described.
